UNITED STATES PATENT OFFICE.

FRANK L. SESSIONS, OF COLUMBUS, OHIO, ASSIGNOR TO JOSEPH A. JEFFREY, OF COLUMBUS, OHIO.

BRUSH-HOLDER FOR MOTORS OR GENERATORS.

No. 813,523.

Specification of Letters Patent.

Patented Feb. 27, 1906.

Application filed May 20, 1903. Serial No. 157,980.

To all whom it may concern:

Be it known that I, FRANK L. SESSIONS, a citizen of the United States, residing at Columbus, in the county of Franklin and State of Ohio, have invented certain new and useful Improvements in Brush-Holders for Motors or Generators, of which the following is a specification, reference being had therein to the accompanying drawings.

- 10 This invention relates to improvements in the devices for holding and feeding the carbon brushes of the sort commonly used in connection with the commutators of electric motors and dynamos.
- 15 The object of the invention is to provide a mechanism which will be of the simplest possible form and with its parts compactly arranged and forming a unitary structure which can be readily put in place in restricted 20 spaces, such as the commutator-chamber in the inclosed or box-like motors.

Figure 1 is a side elevation of a box-motor with a portion broken away, showing a brush-holder mechanism sufficient to illustrate the manner of applying my improvements. Fig. 2 is a side view of a brush-holder. Fig. 3 is a front view. Fig. 4 shows one of the clamping-pieces of the brush detached and in top plan, side elevation, and 30 rear elevation. Fig. 5 illustrates detached the outer part of the follower that advances the brush, showing it in rear elevation, side elevation, and end view. Fig. 6 is a detail view of the insulating contact-piece carried by the follower. Fig. 7 is an enlarged sectional view of a portion of the insulating supporting-block for the brush-holder. Fig. 8 is a face view of the plate employed in securing the insulating-block in place. Fig. 9 illustrates the bed-plate H detached, showing it in side elevation, end view, and top plan. Fig. 10 is a plan view of the base-plate that rests upon the bed-plate, the legs that rise from the base-plate being in section. Fig. 11 45 is a top plan view of the contact-plate P.

In the drawings I have illustrated more or less of a box-motor—that is to say, a motor of the class in which the armature and commutator are inclosed in two field-sections.

50 The armature is shown at A, one of the

field-sections at B, and the other at B'. The armature-shaft a is mounted in bearings C C'. The bearing C extends inward somewhat, as shown at c, from the wall b at the end of the motor.

D indicates the commutator, which is positioned between the end of the armature and the bearing C.

E is a comparatively large block of insulating material, preferably wood. It is formed 60 with a recess or countersink E' upon its inner side. In this there is fitted a metallic plate F.

G represents the fastening-bolts which extend through apertures at e in the block and engage with the metallic nut-plate F, these 65 parts serving to firmly bind the insulating-base to the inner side of the wall b of the motor. After the metallic plate F has been inserted into the recess E' the recess may be filled up or closed by means of insulating material, as indicated at E'', so that all of the 70 surfaces of the insulating-block within the motor-casing will be of insulating material.

H is a bed-plate secured to the insulating-block E. It is formed with guide-ribs h and 75 stops at h'. The part that sustains the brush has a bottom plate I, which is fitted in the guide-plate h, this plate I having a slot at i, through which passes the clamping-bolt J, the latter serving to fasten the plate I in the 80 desired position of adjustment.

The brush is indicated by K. It is held in the box L, supported upon legs M, integral with and rising from the base-plate I. The brush is at its rear or outer end connected to 85 the flexible conductor N, the ends of the latter being respectively secured in clamping-pieces O O', each of these having a clamping-plate, as shown at o, and a side plate, as shown at o', with an aperture for the end of 90 the conductor N. This clamp is formed in two parts in order to provide for the insertion of the brush within it and the efficiency of the clamping action when the two parts are drawn together upon the brush. This drawing of the two parts together and clamping of 95 the brush between them is accomplished by means of a bolt o'', which extends upward through the plate o at the lower side of the brush K and through the brush, and is 100

screwed into the threaded aperture o^3 in the plate o of the upper part of the clamp. It will be seen that the clamping of the brush between the plates is obtained by adjusting 5 the bolt o^2 . This latter may be quickly removed when it is desired to remove the brush. The conductor N is secured to a contact-plate P , slotted at p . The latter is rigidly fastened to the binding-lug Q , which is 10 situated above the carbon and is preferably formed integral with the brush-box L .

R is a binding-screw passing through the slot p in the plate, and R' is a jam-nut adapted to clamp the plate P tightly against the lug Q . The lug is provided with an aperture q , into which is fitted the end of the lead-wire S .

It will be seen that the conductor N connects both parts of the clamp into the electrical circuit from the brush, so as to insure a 20 good and sufficient electrical connection between the brush-clamp and the binding-post.

The carbon brush K is advanced through the box by means of a spring-held follower T . The latter is made in two parts t and t' . The 25 part t is pivoted at U to the legs M , and the two parts $t t'$ are pivoted together at V .

W is a spring connected to the follower and to a stationary holder—as, for instance, a pin or bar on the legs M —and tending to draw the 30 outer end of the follower toward and against the forward end of the carbon brush.

t^2 is a handle on the lower part t of the follower and by means of it the follower can be drawn back at any time—as, for instance, 35 when it is desired to withdraw the carbon and insert another or for other purpose.

The upper part t' of the follower is free to move in one direction around the pivot V , but by means of a shoulder or lug at t^3 is 40 stopped against movement in the opposite direction beyond a predetermined limit. To the upper end of this part t' there is secured a piece of insulating material T' —as, for instance, a small piece of lava. The end of the 45 follower-arm is preferably formed with a cavity, as shown at t^4 , and the insulation has a cylindrical or other suitable form to fit this cavity. It can be fastened in place if it be provided with notches or recesses, as at t^5 , 50 into which the metal at the ends of the cavity t^4 can be bent.

What I claim is—

1. The combination with the brush-holder and the brush, of the pivoted spring-held follower formed in two parts pivotally connected together on a pivot arranged transversely of said brush, the parts being provided with means for limiting the movement of one relative to the other in one direction, and the upper one being adapted to bear against the end of the brush, substantially as set forth.

2. The combination with the brush-holder, the brush, the spring-held follower pivoted

below the brush-box and formed in two parts, the outer part being connected to the inner 6 by a pivot and having its outer end adapted to move around the said pivot in one direction and locked against movement in the other direction when bearing against the brush, substantially as set forth. 7

3. The combination with the brush-holder and the brush, of the pivoted spring-held follower formed in two parts, the lower part being secured by a stationary pivot and having a handle, and the upper part being secured to 7 the lower part by a pivot and locked against movement around said pivot when bearing against the brush, substantially as set forth.

4. The combination with the brush-holder, the brush, the lead-wire-binding lug adjacent 8 to the brush, and the flexible conductor secured to the brush and to said binding-lug, substantially as set forth.

5. The combination with the brush-holder and the brush, of the lead-wire-binding lug 8 adjacent to the brush, the intermediate flexible conductor secured to the binding-lug and secured to the brush by two-part clamp, substantially as set forth.

6. The combination with the brush-holder 9 and the brush, of the lead-wire-binding lug integral with the brush-box, and the flexible conductor interposed between the brush and the binding-lug and bodily detachable from both, substantially as set forth. 95

7. The combination of the brush movable bodily toward the commutator, means for forcing the brush toward the commutator, a brush-holder formed of two parts, and a means for causing them both to tightly clamp 10 the brush, flexible conductors, one connected with each of the clamping parts of the brush-holder, and a contact-plate to which both the said conductors are connected, substantially as set forth. 105

8. In a box-motor, the combination with the armature, the commutator and the inclosing field-sections having the closed end walls supporting the armature-shaft, the bearing for the shaft projecting inwardly from the closing wall, the insulator arranged to overlap the said bearing and secured from the exterior to the said closing wall, the bodily stationary brush-holder adjustably secured to the said insulator, and the spring-held follower adapted to bear against the brush in the holder, substantially as set forth. 115

9. The combination with the brush-holder and the brush, of the spring-held follower bearing against the brush and having at its end adjacent to the brush a cavity in which is situated an insulator held in position by the bent-in end walls of said cavity. 12

10. The combination with the brush-holder, the brush and the spring-held follower bearing against the brush, of the piece of in- 125

ulating material T' having the notches t^5 in its ends, the upper end of the said follower having a cavity t^4 into which the said piece of insulating material is fitted and the end walls 5 of which are bent into the notches t^5 of said piece of insulating material to fasten it in place.

In testimony whereof I affix my signature in presence of two witnesses.

FRANK L. SESSIONS.
